UNITED STATES PATENT OFFICE.

GEORGE S. STRONG, OF NEW YORK, N. Y.

BOILER.

SPECIFICATION forming part of Letters Patent No. 655,589, dated August 7, 1900.

Application filed August 26, 1899. Serial No. 728,536. (No model.)

To all whom it may concern:

Be it known that I, GEORGE S. STRONG, a citizen of the United States of America, residing in the city and county of New York, 5 in the State of New York, have invented certain new and useful Improvements in Boilers, of which the following is a true and exact description, reference being had to the accompanying drawings, which form a part thereof.

10 My invention relates to the construction of boilers having the general characteristics described and shown in my Patent No. 631,830, dated August 29, 1899.

The object of my invention is to improve 15 upon the construction of my patented boiler, providing for a more energetic circulation of water in the boiler, for a stronger construction of the fire-box portion of the boiler, for ready and convenient access to the tubes, 20 and for the separation of the water from the steam and prevention of an injurious amount of water in the steam-dome.

The nature of my improvements by which 25 the above ends are secured will be best understood as described in connection with the drawings, in which they are illustrated, and in which—

Figure 1 is a vertical longitudinal section 30 through the center of the boiler, taken as on the line 1 1 of Fig. 3. Fig. 2 is a view, on a larger scale, of a detail shown in Fig. 1. Fig. 3 is a front view of the boiler, the portion to the left being shown with the shell of the fire-box removed and the portion to the right 35 being shown in section on the line 3 3 of Fig. 4. Fig. 4 is a plan view taken on the irregular section-line 4 4 of Fig. 3. Fig. 5 is a longitudinal section through the end of one 40 of the tubes and devices connected therewith, taken as on the line 5 5 of Fig. 6; and Fig. 6 is a cross-section through the tube, the portion to the left of the central line being shown on the section-line 6 6 of Fig. 5 and the portion to the right of the central line 45 being shown on the line 6 6 of Fig. 5.

A and A' indicate the headers, between which the fire-box is situated and to the rear one of which, A', the boiler-shell D is secured, as shown. In my present construction 50 I prefer to make the rear header of considerably-greater size than the front header, as is clearly shown in Figs. 1 and 3.

B B indicate two sets of water-tubes connecting the lateral sides of the front and rear headers and preferably inclined upward from the rear to the front header, as shown, to insure that the water will circulate freely from back to front through them. These tubes are preferably also arranged, as shown in Fig. 3, so that they arch over 60 the grate and the bridge extending above the grate.

c is a set of water and steam circulating tubes connecting the upper central portions of the front and rear headers and preferably 65 set, as shown, so that they incline upwardly from the front to the rear. The inclined tubes c are situated between the lateral tubes B B and lapped past them at the front of the fire-box, forming a lattice construction, which 70 greatly increases the strength of the structure. The outer walls or jacket of the fire-box is preferably formed, as shown, of a series of hollow tiles, as indicated at P, the openings being indicated at p, these tiles 75 opening into the fire-box beneath the grate at P², and at some upper portion—for instance, at P³—opening to the atmosphere, so that an energetic circulation of air occurs through the openings p into the fire-box, serving the 80 double purpose of supplying the fire-box with heated air and of keeping the outer jacket of the fire-box comparatively cool.

J J, &c., indicate a water-tube grate, the tubes being connected with the headers, as 85 shown, J' J', &c., indicating rotatably-anchored bars situated between and below the water-tubes of the grate, by means of which the ashes are cut out and removed.

F F, &c., indicate a series of water-tubes 90 connected with the front and rear headers and extending across the fire-box, as shown, to afford supports for a forwardly and upwardly inclined bridge-wall G, which extends over the rear part of the bridge and by means 95 of which the products of combustion are forced forward in the fire-box before they can pass beyond and above the bridge into the combustion-chamber and fire-tubes of the boiler-shell, said combustion-chamber being 100 indicated at E' and the fire-tubes at E E.

I indicates a bridge or rear wall supported on the grate and reaching nearly but not quite to the under side of the bridge-wall G.

Back of this wall and opening into the fire-box beneath the bridge-wall is an air and steam passage, (indicated at I'), I⁴ indicating a steam-pipe having openings along its top 5 by which steam can be thrown into the passage I' and out through the nozzle I² beneath the bridge-wall, and I³ indicating a damper for regulating the admission of air.

B³ indicates charging-doors opening into 10 the furnace through the front header A.

D, as before stated, is the boiler-shell connected with the rear header, D' being the steam-dome, secured to the top and sides of the front end of the boiler-shell D and also to 15 a brace-plate (indicated at Q', Fig. 1) and a downwardly-extending plate or plates, (indicated at Q,) said plate being inclined rearwardly and extending nearly but not quite to the normal water-line in the shell D. The 20 function of this plate is to intercept the steam, largely mixed with water, coming from the tubes c, which open at or near the water-line and throw the water downward in contact with the water in the boiler-shell, with 25 which it merges. Preferably I provide also a substantially - horizontal and perforated plate (indicated at Q²) extending rearwardly from the lower edge of the plate Q and through the perforations in which the steam escapes 30 into the steam-space of the boiler. By preference I also supply a transversely-extending plate Q³, extending across the boiler-shell at the rear of the plate Q² and serving as a wash-plate, which in the starting and stopping of 35 the engine prevents such surges of the water in the boiler as would be likely to throw it into the steam-dome D'.

In Figs. 4 and 5 I have illustrated the device which I prefer to use in order to make 40 the fire-box tubes readily accessible. Tubes (indicated in Figs. 5 and 6 at B) are expanded into the headers and have their ends (indicated at B²) open, but finished so that the edges will lie in a plane perpendicular to the 45 axis of the tube. Slots, as indicated at B', enable the tubes to communicate freely with the headers, into which they are expanded. R indicates a cap formed with an annular slot r, adapted to fit over the end B² of a 50 tube, said slot having, preferably, a copper gasket R' secured in its bottom. The cap R is made with a threaded perforation R² on its inside and provided also with a head R³, adapted to give hold to a wrench. S is a bolt 55 having a threaded end S', adapted to be engaged by and screwed into the threaded perforation R² in the cap, and the bolt is also provided with a laterally-extending hook end S², which is adapted to engage the edge of 60 one of the slots B'. Preferably I also secure a pivot-pin S³ in the bolt and pivot thereon a supplemental hook, (indicated at S⁴), having, like the bolt S, a hooked end S², which, how- 65 ever, is turned in the opposite direction to that of the bolt proper and adapted to engage the edge of the opposite slot B'. By

preference I form this supplemental hook S⁴ with laterally-projecting ears or lugs S⁵ and S⁶, by pushing against which from the open end of the tube the supplemental hook can 70 be turned outward or inward, as may be desired.

The use of the hooked bolt and cap to close the end of the tube is simple and obvious. The hook or hooks S² are engaged in the end 75 of the slot and the cap then screwed on the threaded end of the bolt until it is drawn tight against the end of the tube and a good joint effected. When it is desired to get at the inside of the tube, the cap is unscrewed, the 80 hooked bolt removed, and the tube is then freely open for cleaning purposes.

Having now described my invention, what I claim as new, and desire to secure by Letters Patent, is—

1. A boiler having in combination front and rear headers, as A and A', between which the fire-chamber is situated, a set of water and steam tubes c connecting the central upper portions of the headers and inclined upward 90 from the front to the rear header, said tubes forming the top of the fire - chamber, two sets of water-tubes B B connecting the lateral sides of the headers and forming the sides of the fire-chamber, said tubes being inclined downward from the front to the rear header and lapping part of the front ends of the tubes c so as to form a lattice-bracing for the fire-box and a capacious and energetic 95 circulating device for the water, and a boiler-shell secured to the rear header and having fire-tubes connecting with the fire-chamber. 100

2. A boiler having front and rear headers, as A A', between which the fire-chamber is situated and boiler-shell, as D, secured to the 105 rear header, a set of water and steam tubes, as c, connecting the tops of the headers and forming the top of the fire-chamber, two sets of water-tubes, B B, connecting the lateral sides of the headers and forming the sides of 110 the fire-chamber, and a deflecting-plate Q secured to the top of the boiler-shell D in front of the tubes c and extending nearly to the water-line.

3. A boiler having front and rear headers, 115 as A A', between which the fire-chamber is situated and a boiler-shell, as D, secured to the rear header, a set of water and steam tubes, as c, connecting the tops of the headers and forming the top of the fire-chamber, two sets of water-tubes B B, connecting the lateral sides of the headers and forming the sides of the fire-chamber, a deflecting-plate Q secured to the top of the boiler-shell D in 120 front of the tubes c and extending nearly to the water-line, and a substantially-horizontal perforated plate Q² extending back above the water-line from the lower edge of plate Q. 125

4. A boiler having front and rear headers, 130 as A A', between which the fire-chamber is situated and a boiler-shell, as D, secured to the rear header, a set of water and steam

tubes, as *c*, connecting the tops of the headers and forming the top of the fire-chamber, two sets of water-tubes, *B B*, connecting the lateral sides of the headers and forming the 5 sides of the fire-chamber, a deflecting-plate *Q* secured to the top of the boiler-shell *D* in front of the tubes *c* and extending nearly to the water-line, a substantially-horizontal perforated plate *Q*² extending back above the 10 water-line from the lower edge of plate *Q* and swash-plate *Q*³ secured across the boiler at the end of plate *Q*².

5. A boiler having in combination front and rear headers, as *A* and *A'*, between which the 15 fire-chamber is situated, a boiler-shell, as *D*, secured to and opening into the rear header, a set of water and steam tubes *c* connecting the central upper portions of the headers and inclined upward from the front to the rear 20 header, said tubes forming the top of the fire-chamber, two sets of water-tubes *B B* connecting the lateral sides of the headers and forming the sides of the fire-chamber, said tubes being inclined downward from the front 25 to the rear header and lapping past the front end of the tube *c* so as to form a lattice-bearing for the fire-box and a capacious and energetic circulating device for the water, and a deflecting-plate *Q* secured to the top of the

boiler-shell *D* in front of the tube *c* and extending nearly to the water-line. 30

6. A boiler having in combination front and rear headers, as *A* and *A'*, between which the fire-chamber is situated, a boiler-shell, as *D*, secured to and opening into the rear header, 35 a set of water and steam tubes *c* connecting the central upper portion of the headers and inclined upward from the front to the rear header, said tubes forming the top of the fire-chamber, two sets of water-tubes *B B* connecting the lateral sides of the headers and forming the sides of the fire-chamber said tubes being inclined downward from the front to the rear header and lapping past the front end of the tubes *c* so as to form a lattice-bracing 40 for the fire-box and a capacious and energetic circulating device for the water, a deflecting-plate *Q* secured to the top of the boiler-shell *D* in front of the tube *c* and extending nearly to the water-line, and a substantially-horizontal perforated plate *Q*² extending back above the water-line from the 45 lower edge of plate *Q*. 50
